UNITED STATES PATENT OFFICE.

FRED T. KITT, OF SEATTLE, WASHINGTON, ASSIGNOR, BY MESNE ASSIGNMENTS, TO
AMERICAN CAR AND FOUNDRY COMPANY, OF NEW YORK, N. Y., A CORPORATION
OF NEW JERSEY.

ELECTRODE FOR RIVET HEATERS.

Application filed March 6, 1926. Serial No. 363,670.

To all whom it may concern:

Be it known that I, FRED T. KITT, a resident of Seattle, county of King, and State of Washington, have invented a new and useful Improvement in Electrodes for Rivet Heaters, of which the following is a full and complete description, reference being had to the accompanying drawing, forming a part of this specification.

10 My invention relates to electrodes or jaws for a rivet heater similar to the one described in application Serial No. 319,933 filed by me on August 26th, 1919, the object being to provide means whereby rivets or 15 the like may be conveniently inserted in an electric circuit in such a manner that a large volume of current can be forced through them for the purpose of heating the same. Another object is to provide means for cooling the points of contact which, in the ordinary process of heating by means of an electric current, tends to overheat.

20 Fig. 1, indicates the secondary of a transformer, which terminates in a pair of jaws 25 for holding rivets, as shown. Fig. 2 shows a modification of these jaws. Fig. 3 is an enlarged view of Fig. 2 taken, partly in cross section, through the line 1, with the addition of a rivet in order to show the 30 method of holding same in the jaws as well as the application of the cooling means above referred to. Fig. 4 is a cross-section showing a detail of the contact surface for the head of the rivet.

35 I have not considered it necessary to show any other details of the transformer, as any one skilled in the art will understand the device from the drawing and this description.

40 In Fig. 1, 1 indicates a single turn of copper or other good conducting material, which terminates in jaws 4 and 5, which latter are at an angle to each other. The upper jaw 4 has a series of notches which form 45 short sections parallel with and at various distances from the lower jaw 5. These notches are for the purpose of accommodating rivets of different lengths. By inducing a heavy current in this closed circuit, composed of the copper secondary and the rivet,

as shown, the latter can be heated to the melting point if desired.

In the modification shown in Fig. 2 the jaw is not notched but is equipped with a movable block 3, which can be fastened at any point on the jaw 4, in order to accommodate rivets of different lengths. In the enlarged view Fig. 3, 2 represents a rivet with its head in contact with block 3, and its point with jaw 5. It is well known that when a current is passed through a series of conductors in simple mechanical connection with each other, the points of contact tend to heat faster than any other part of the circuit owing to the contact resistance, therefore, in heating rivets by the method described, the two ends will become heated much sooner than the body of the rivet. This is especially true of the point as the head, being larger, radiates heat faster and thus keeps comparatively cool. To overcome the danger of overheating the point, I have made the lower jaw 5, with a depression for holding a small quantity of tin, lead or the like where the point of the rivet makes contact with the jaw. When the rivet becomes hot, this metal liquefies and forms a bath for the point of the rivet as indicated by the dotted lines 8. This improves the contact and forms a radiator for a certain amount of heat all of which tends to keep the point from burning. By this method it is possible to get the body of the rivet hotter than the point which is a great advantage.

Fig. 4 represents a slight modification of the block 3, being a cross section also through the line 1, Fig. 2. I show here an oval shaped depression in the block designed to fit snugly the head of a rivet in order to assure better contact and to hold the rivet more securely. This oval depression may be made either in the block 3, as indicated, or in the faces of the notches in jaw 4, Fig. 1.

While I have mentioned only the heating of rivets in this specification, I believe the idea of cooling the points of contact in an electric circuit, used for heating, is entirely new and may be applied to the heating of many other articles, therefore, I do not wish to limit myself, in this application, to

the heating of rivets but to cover broadly the cooling idea described.

Having described my invention, what I claim is, as follows:

5. 1. In an electric heater, the combination of means whereby current may be passed through an element for the purpose of heating the same, and means for cooling a point of contact with a bath of molten metal.
10. 2. In an electric rivet heater, a secondary coil having angularly disposed electrodes and a cooling bath of molten metal carried by one of said electrodes.
15. 3. In an electric rivet heater, a secondary coil having angularly disposed jaws provided with parallel rivet engaging surfaces one of said surfaces being adjustable to vary the normal opening between said surfaces.
20. 4. In an electric rivet heater, a secondary coil having angularly disposed jaws provided with parallel rivet engaging surfaces adapted to engage rivets at different distances from the apex of the angle made by said jaws.
25. 5. In electrodes for an electric rivet

heater, the combination of an upper and a lower jaw extending at an angle to each other and a movable block adapted to fasten to said upper jaw as shown and described.

6. In an electric rivet heater, a secondary ³⁰ coil having angularly disposed jaws provided with parallel rivet engaging surfaces and means to adjust one of said surfaces along its supporting jaw.

7. In an electric rivet heater, a secondary ³⁵ coil having terminal jaws, a rivet engaging surface movable along one of said jaws and a cooperating rivet engaging surface carried by the other of said jaws.

8. In an electric rivet heater, a secondary ⁴⁰ coil having terminal jaws provided with cooperating rivet engaging surfaces, one of said surfaces being shiftable along its supporting jaw to vary the normal opening between said surfaces.

FRED T. KITT.
